THERMIC SIPHON AND METHOD OF MAKING THE SAME

Filed May 27 1929 2 Sheets-Sheet 2

UNITED STATES PATENT OFFICE

WALTER H. HINSCH, OF CHICAGO, ILLINOIS, ASSIGNOR TO LOCOMOTIVE FIREBOX COMPANY, OF CHICAGO, ILLINOIS, A CORPORATION OF DELAWARE

THERMIC SIPHON AND METHOD OF MAKING THE SAME

Application filed May 27, 1929. Serial No. 366,146.

This invention relates to improvements in thermic siphons and method of making the same and it consists of the matters herein-after described and more particularly 5 pointed out in the appended claims.

The term "siphon" as employed herein, designates a flat, hollow, substantially triangular structure or element particularly adapted for use in locomotive type of boiler 10 fireboxes for increasing the water circulation and steam efficiency thereof. Such a siphon is fully shown and described in U. S. Letters Patent #1,337,720 of April 20, 1920 granted to John L. Nicholson. It generally 15 includes a tubular bottom portion which terminates in a tubular extension or neck adapted for connection to the inner throat sheet of the firebox, and a flat hollow body with an elongated discharge mouth which 20 opens through the crown sheet of the firebox.

Heretofore it has been the practice in making such siphons to first cut a single sheet of metal into pattern shape so that when folded along its median line and otherwise 25 operated upon and flanged to siphon form, it was welded along the proper meeting edges, which edges were disposed in the median plane of the finished siphon.

In this manner of making the siphons, 30 great care had to be exercised because of the time, labor and material costs involved. Again each size of siphon required special templets and patterns and this materially increased the cost of manufacture and made 35 the production of each size of siphon a special "job" so to speak.

The primary object of the invention is to 40 provide an improved siphon of this kind and method of making the same, wherein the cost of production is greatly decreased by a saving in time and material and a siphon is produced wherein the lines of welding are removed from those points subject to the greatest buckling strains and stresses and can be 45 advantageously positioned in the flat sur-

face thereof which can be more conveniently and strongly stayed.

Another object of the invention is to provide a siphon which may be initially formed in a plurality of sections, capable of being 50 produced by die work and then cut and trimmed to size to provide any desired size of siphon within a practical range from one of maximum size and this without materially increasing the total length of line of or 55 disposing said line of weld in the planes most effected by strains and stresses normally tending to rupture them.

The above mentioned objects of the invention as well as others together with the many 60 advantages thereof, will more fully appear as I proceed with my specification.

In the drawings:—

Fig. 1 is a longitudinal vertical sectional view through a locomotive firebox, embodying therein a siphon made in accordance with my invention.

Fig. 2 is a view in side elevation on an enlarged scale of a siphon embodying my invention, ready for assembly into a firebox. 70

Fig. 3 is a vertical sectional view through the same, on an enlarged scale as taken on the line 3—3 of Fig. 2.

Fig. 4 is a detail horizontal sectional view also on an enlarged scale as taken on the line 75 4—4 of Fig. 2.

Figs. 5—6 and 7 respectively are perspective views of the several parts or sections of the siphon in an advanced stage of their manufacture disposed in grouped relation in 80 accordance with the positions they occupy in a finished siphon.

Figs. 8 and 9 are perspective views of the parts shown in Figs. 5 and 6 respectively as they are initially formed.

Fig. 10 is a view in elevation of a length of seamless tubing from which the siphon part shown in Fig. 7 is made and before any operations have been performed thereon.

Fig. 11 is a view in elevation of the tubing 90

shown in Fig. 10 after the first step has been performed thereon as by swedging one end thereof to reduce its diameter.

Fig. 12 is a view which may be considered 5 as a top plan view of the tube after it has been slit longitudinally along the unswedged part thereof and off center with respect to a vertical plane passing through the axis of the tube.

10 Fig. 13 is a view in side elevation of the tube after it has been opened up along the slit to form upstanding side walls of different heights thereon.

Fig. 14 is a vertical sectional view through 15 the tube shown in Fig. 13, as taken on the line 14—14 thereof.

Referring now to the locomotive firebox illustrated in Fig. 1, the same has a fire chamber which extends from the back sheet 20 1 to the flue sheet 2 and from one to the other of the side sheets 3, with a grate or bottom as indicated by the dotted line 4. Said grate extends from the back sheet to an inner throat sheet 5 which is normally 25 formed as the bottom extension of the flue sheet 2. The top of the firebox is formed by the transversely curved crown sheet 6 which extends from back to flue sheet. The firebox is enclosed by the top plate 7 and 30 usual outer side plates (not shown), and the outer throat plate 8 and outer back plate 9 which provide the wrapper therefor. In the plates 1 and 9 respectively, is formed the usual fuel door opening and to the flue sheet 35 are attached the usual flues 10 through which the products of combustion are drawn by the usual exhaust nozzle in the smoke box in the manner well known.

The various plates before mentioned, 40 together with the fire sheets or walls of the firebox define the several water legs of the boiler, namely the front leg or throat 11, side legs, and back water leg 12 all closed at the bottom by the mud ring 13. The inner sheets of the firebox including the crown 45 sheet are joined to or stayed from the outer sheet by means of stay bolts 14.

My improved siphon or element is indicated as a whole by the numeral 15, it being 50 understood that one or more of such elements may be located in the firebox, the number of course being dependent upon the size of the firebox. Said element extends longitudinally of the firebox and normally occupies an 55 upright position therein.

The siphon as herein shown when considered as an entirety includes an upwardly and rearwardly inclined tubular neck or bottom 60 16 and a progressively upwardly enlarging flat body portion 17, having a relatively high or long front end 18 and a relatively low or short rear end 19. The lower front end part of the bottom portion 16 is a closed tube and constitutes the inlet neck 20 for 65 the siphon which is in open and unobstructed

communication with the front water leg 11. Preferably said neck is fixed in a flexible diaphragm portion 21 in the inner throat sheet 5.

The flat tubular body part is preferably 70 flanged at its top as at 22 to fit within an opening provided therefor in the crown sheet 6 and certain of the stay bolts 14 are employed to stay said flange from the top sheet 7 of the boiler. Such an element was heretofore made from a single sheet of metal cut to a pattern, then folded, flanged and welded together, the welding usually extending along the top of the neck and up the front 75 end of the body. Where the element was cut off or truncated at its rear end, a line of welding was there provided. When such a siphon was in position in a firebox, the lines of welding were effected by strains and stresses due to expansion and contraction under 80 temperature changes. Such welding not only sometime gave away but also presented rough spots or surfaces on the inside of the siphon, in line with the natural flow or passage of water therethrough, and thus formed 85 ideal locations for the initial accumulation of scale and sediment which of course is objectionable.

In making up my improved siphon under 90 the steps of my improved method, I make 95 the same in a plurality of parts or sections producible in the rough by coacting dies, after which they are trimmed and fitted to size, then flanged and assembled and thereafter welded, the welding being disposed for 100 the greater length upon the flat sides of the element instead of upon the rounded ends thereof.

Preferably I make the siphon in three 105 parts or sections as this number gives more latitude in trimming and fitting the said parts or sections to the desired size. For convenience in referring to the said parts I have designated them as the bottom tubular or neck part (16) the flat body part (17) 110 and rear end part (19) all before mentioned.

In Fig. 10 to 14 inclusive is illustrated the several steps in making up the bottom tubular or neck part 16. Said part is made from a piece of seamless steel tubing 23 (see Fig. 10) 115 which is preferably oversize in length and diameter with respect to the maximum size of the part to be made. I first swedge down one end of said tube as at 24 in Fig. 11 to that diameter required for the inlet neck 20 of the 120 finished siphon, said end being connected to the remainder of the tube as by a tapered portion 25.

Thereafter the other end of the tube is slit 125 longitudinally as at 26 (see Fig. 12 which is to be considered as a top plan view) along a line offset with respect to a vertical plane 27 passing through the axis of the tube. Said slit terminates at its inner end in said plane and adjacent the swedged down end of the 130

tube. Those portions of the tube on both sides of the slit are then opened or upset into parallel spaced relation to provide side wall parts 28 and 29 respectively, of different heights arranged an equal distance on each side of the axis of the tube. During this opening up of said side wall parts the remainder of the tube is reduced in diameter to provide the excess material necessary for said side walls 10 and also to bring it down to the diameter of the swedged end 24, all as best shown in Figs. 13 and 14. The side walls 28 and 29 are spaced apart a distance equal to the spacing of the walls of the body and rear end parts 15 of the finished siphon to be made and as the diameter of the portion 20 is greater than the spacing between the walls 28 and 29, it is apparent that lines of fold 30 and 30 develop along each side thereof. 20 During this opening up of said side walls, the point 27 moves radially away from the axis of the tube and this point is gradually merged into the top side of the swedged end portion 24 thereof as by a rounded corner or 25 curve 31.

In making up the body 17, I provide a piece of boiler plate of desired shape and size and fold it along its median line to form a substantially U shaped blank having a rounded end 32 and side walls 33 and 34 respectively as best shown in Fig. 9. In this respect the blank is higher at its front or rounded end than it is at its rear end, so that the bottom edges of the side walls converge toward the plane of 35 the top edges of said walls, which top edges are disposed at substantially a right angle with respect to the rounded front end thereof. Thereafter the top marginal portions of said side walls and rounded end wall are 40 turned over outwardly to form a flange 35 thereon as best shown in Fig. 6. In such a partly finished body blank the side walls are of the same shape and area so that they may be trimmed to desired dimensions. Preferably in the trimming of said partly finished body blank, I cut off the rear end margin and the bottom margin of one side wall, so that it becomes of a lesser area as indicated by the dotted lines 36 in Fig. 6 whereby the rear end 45 and bottom marginal edges of the other wall is offset rearwardly beyond and also below the like edges of the trimmed off side wall. In trimming off the bottom margin of the side wall 34, the relative heights of the side walls 50 28 and 29 of the bottom tubular portion are taken into consideration so that the walls 33 and 34 will match up therewith.

In making up the shorter rear end part or section 19, I take a piece of boiler plate of 55 desired shape and size and by means of coacting dies form it into approximately a triangular shaped blank such as shown in Fig. 8 open at its top and front and closed at its rear and bottom. Such a blank includes side walls 37 and 38 respectively connected

at the rear by a rounded wall 39 and connected at the bottom by a rounded wall 40. In this respect it is pointed out that while said rear wall and bottom wall extend at different angles, the difference is so slight that the 70 partly finished blank is substantially triangular in shape as before mentioned. It is also pointed out that the bottom wall is swedged to bulge or enlarge the same at 41 to match up with the like portion of the bottom tubular portion 16.

With the rear end part thus far completed, I turn the top marginal parts of the side walls 37 and 38 and of the rear wall 39 over and outwardly to provide a flange 42 thereabout as shown in Fig. 5. Thereafter I cut away the front end portion of the side wall 37 as indicated by the dotted line 43 in said Fig. 5 so that the offset between the front edges of the walls 37 and 38 match up with the offset between the rear edge of the walls 33 and 34 of the body 18. In thus cutting away of the front end marginal part of the wall 37, the portion 43 thereof is cut at less than a right angle to match up with the rear end of the bottom tubular portion, which is trimmed to fit. 85

With all of said parts trimmed to fit and match up with one another, they are then assembled in grouped relation and secured together by lines of welding 44 and 45. In this respect it is pointed out that the said lines of welding are not disposed at the end portion of the siphon but are all on flat surfaces, the only weld on a rounded portion being where the weld crosses the rear end of the bottom tubular portion and the portion 41 of the rear end part 19. Thus no welding is located in the plane of the ends of the siphon which plane is disposed in the line of greatest stresses and strains. 95

After the parts have been thus welded, they are drilled through from one side to the other with the aid of a drilling templet after which the various walls are connected together by stay bolts 46. It is to be noted from Fig. 2 that the offset rear end portion of the side walls 33 and 34 of the body are connected to the offset front end portion of the side walls 37 and 38 by means of two rows of stay bolts while the offset bottom ends of said walls 33 and 34 are connected to the offset side walls 28 and 29 of the bottom tubular portion by a single row of stay bolts. 115

With the several parts initially produced for a maximum size of siphon it is apparent that such a siphon or a smaller one can be produced therefrom after the desired dimensions are known, by cutting and trimming down the several parts. Thus each new siphon to be made does not require special patterns, and templets and forming machines but may be made up from parts of maximum size trimmed to fit and all in accordance and upon machines now found in modern boiler 120 125 130

shops. Therefore the cost of production is lowered and a better siphon is produced and one wherein the lines of welding are unaffected by contraction and expansion due to 5 temperature changes.

While in describing the invention, I have referred in detail to the form, construction and arrangement of the various parts, as well as to the several steps in making up a siphon, 10 the same is to be considered merely as illustrative so that I do not wish to be limited thereto except as may be specially set forth in the appended claims.

I claim as my invention:—

15. 1. The method of making a thermic siphon which consists in providing a tubular portion having laterally spaced side walls and a transversely rounded bottom, providing at least two body sections each including laterally spaced side walls, trimming end and bottom portions of said side walls of each body section to fit the like walls of said tubular section and also to fit each other to make them match and then securing the matched edges 25 of the several sections together. 80

2. The method of making a thermic siphon which consists in providing a tubular portion having laterally spaced side walls and a transversely rounded bottom, providing at least 30 two body sections each including laterally spaced side walls, trimming end and bottom portions of said side walls of each body section to fit the like walls of said tubular section and also to fit each other to make them 35 match, welding the matched edges of the said sections together and then staybolting opposite walls of said sections together. 85

3. The method of making a thermic siphon which consists in providing a bottom tubular 40 section with upstanding side walls and a body section and rear end section also having side walls, trimming all of said side walls to make their edges match, bringing said matched edges together in completed siphon relation 45 and then welding said matched edges. 90

4. The method of making a thermic siphon which consists in providing a bottom tubular section with upstanding side walls and a body section and rear end section also having side 50 walls, trimming all of said side walls to make their edges match, bringing said matched edges together in completed siphon relation, welding said matched edges together, forming registering holes in said side walls and 55 then applying staybolts in said holes. 95

5. The step in the method of making the nose part of a thermic siphon which consists in forming a sheet to provide a member having spaced side walls which are connected together at the bottom and at one end by rounded portions with a bulge formed in the rounded bottom. 100

6. The step in the method of making a thermic siphon which consists in forming a 65 metal sheet into a U shape with side walls of 105

greater dimensions than is desired and in then removing marginal portions of said side walls and flanging other portions thereof. 110

7. A siphon formed of three body parts 70 each including spaced side walls and a rounded connecting wall, the meeting edges of said walls being welded together. 115

In testimony whereof, I have hereunto set my hand, this 24th day of May, 1929. 120
